W. C. CUTLER.
POCKET CARD CASE.
APPLICATION FILED JAN. 23, 1917.

1,234,296.

Patented July 24, 1917.

UNITED STATES PATENT OFFICE.

WILLIAM C. CUTLER, OF NORTH GLENDALE, CALIFORNIA.

POCKET CARD-CASE.

1,234,296.

Specification of Letters Patent.

Patented July 24, 1917.

Application filed January 23, 1917. Serial No. 144,077.

To all whom it may concern:

Be it known that I, WILLIAM C. CUTLER, a citizen of the United States, residing at North Glendale, in the county of Los Angeles and State of California, have invented new and useful Improvements in Pocket Card-Cases, of which the following is a specification.

My invention relates to improvements in pocket card cases; and the objects of my improvements are, to throw out the cards automatically one at a time by opening the cap or top of the case; to provide an inexpensive easily attachable device which can be inserted into any common pocket card case; to provide an attachment which operates automatically with the cover of the case or by suitable means projecting through the case operated by hand; to improve common pocket card cases by a small attachment for automatically discharging one card at a time; to assure clean and unbroken cards; to prevent scratching of the cards by providing suitable card shifting means; to provide a card case which will automatically discharge one card at a time by opening the case; the invention consisting in the construction, combination and arrangement of devices hereafter more fully described and claimed, and illustrated in the accompanying drawing, in which—

Figure 1 is a side elevation of the attachment in my card case.

Fig. 2 is a section of the spring-like attachment-plate without the shifting mechanism cut on line 2—2 of Fig. 1.

Fig. 3 is a vertical section of the lower end of the card shifting bar in slightly enlarged scale.

Fig. 4 is the bottom-end plan view of the shifting bar in Fig. 3.

Fig. 5 is the end view of the shifting roller.

Fig. 6 is the side view of the shifting roller of Fig. 5.

Fig. 7 is a card case with my attachment inserted in vertical cross section.

Fig. 8 is a vertical section of a case with my attachment inserted and connected to the top.

Fig. 9 is a front elevation of a spring attachment for the device illustrated in Fig. 2, this construction being a slight modification of the attachment of Figs. 1 and 2.

Fig. 10 is a slight modification of the attachment shown in Figs. 1, 2, 7 and 8, the

upper end of the operating rod being not connected to the cover, but instead projecting through the case for hand operation, a section of the case being illustrated with the slightly modified operating rod.

Fig. 11 is the side elevation of the case-section of Fig. 10.

Fig. 12 is a horizontal cross section of a modified form of the lower end of the operating rod, illustrated in Figs. 3 and 4, the pivot projecting through the case and being enlarged for hand operation.

Fig. 13 is a section of the pivot in Fig. 12 on line 13—13.

Fig. 14 is a front elevation of the upper end of the operating rod.

Similar numbers refer to similar parts throughout the several views.

The frame attachment 1, see Figs. 1 and 2, is formed to fit in the case as illustrated in Figs. 7 and 8, the upright bar 2 being of the same length as the case body 3, the lower bend 4 is of the length to fit between the two flat walls of the case, and the rest of the frame is again of the same length as the length of the case-body, this latter end, being designated 5, is at the same time formed to press the inserted cards in a case toward the operating parts of the attachment. The upright 2 is provided with a slot 6, see Fig. 2. The lower end 8 of the operating rod 7 is provided with a pivot 9, which fits with the neck 10 slidingly in the slot 6, while the head 11 is made slightly larger, to hold the operating rod in position, in sliding relation to the upright 2. Lugs 12 are formed sidewise on the lower end 8 of the operating rod, see Figs. 3 and 4, having a pin disposed therein. A roller 14, having a bore 15, fits turnably on the pin 13. A needle 16 is formed on or suitably secured to the roller. Projections 17 and 18 are also formed on the roller to stop the turning motion of the roller at desired positions.

The spring attachment 19 is riveted to the short bend 4 of the frame attachment 1, as indicated at 20, or, as will easily be understood, the spring attachment may be of one piece with the frame attachment and bent to the form shown in Fig. 9. The upper end 21 of the spring attachment is formed to serve as the opening spring for the case-top, the bent-end 21 pressing normally against the inner side of the top or cover of the case. It will be understood that this bent spring end is not necessary in cases where a

spring is inserted in the hinge of the case or other places which give the same results, namely to open the case after the push button 22 has been pressed and having thereby released the cover 23.

The upper end 24 of the operating rod 7 is pivotally connected to the cover 23 as shown in Figs. 7 and 8.

Having released the cover by the push-button 22, the operating rod 7, being pivotally connected to the cover by the pivot 25, is also lifted, the cards being pressed against the roller 14 by the spring end 5 of the frame attachment 1, the roller will naturally turn and the needle will come to engagement with the card closest to the roller. The roller will then not be able to turn any further as the projection 18 will in this position rest against the lower end 8 of the operating rod 7. The operating rod being pulled further, naturally throws also the card out of the case to a suitable extent that it can be taken by hand.

Closing the cover pushes also the operating rod back to its starting position, and the roller, rolling along the cards in the case, naturally turns back, taking the needle away from the cards. To prevent the roller from turning further than necessary, the second projection 17 is formed on the roller resting against the operating rod when the needle is in a position out of engagement with the cards.

In the slightly modified construction, illustrated in Figs. 10 and 11, the operating rod is not connected to the cover of the case, an opening 26 is provided instead, in the case. The upper end of the operating rod is bent to project through the opening 26 forming a handle or thumb-piece 27. In this construction the cover is opened in the usual manner, but the cards are shifted or thrown out of the case by a movement of the thumb or finger touching the projection 27 of the operating rod.

Another slight modification is illustrated in Figs. 12 and 13. In this construction the pivot 9 on the lower end of the operating rod is enlarged to project through the case forming a thumb piece for operating by hand instead of automatically by the cover of the case. It will be understood that in this construction the case has to be provided with a suitable slot similar to the slot 6 in the frame attachment.

It will also easily be understood that in this construction, the operating rod can be eliminated above the lugs 12. In such case, the pivot is made with a flat section in the neck as indicated at 28, preventing the roller from twisting. But, preferably, the operating rod is provided with a slot 29 on the upper end as illustrated in Fig. 14 fitting slidably on the pivot 25 on the cover 65 of the case. In this construction it is pref-

erable to provide a slot 30 in the cover. This construction making it possible to throw out cards by opening the cover or also to throw out cards by shifting the thumb piece 31 on the pivot 9 of the operating rod. Shifting the cards by the pivot 9, the operating rod simply slides with the slot in the upper end of the operating rod on the pivot 25 on the cover.

From the above it will be understood that the card shifting attachment in this application can be inserted into any size of a card case, the frame attachment can easily be bent to fit in any width of case, the spring attachment is made to be fitted in any width, the end 32, see Fig. 9, can be cut to fit any size of case, this holding the frame attachment of Figs. 1, 2, 7 and 8 in correct position in the case, without being riveted in.

It also does not matter if a case is provided with a hinge or not, if opening sideways or endwise, as will also easily be understood from the preceding description of my attachments; and I do not want to claim any particular card case, but only an attachment for any kind of card case.

Having thus described my invention, I claim:

1. A card shifting attachment consisting of a spring member removably fitting into different sizes of card cases, a card shifting mechanism slidably mounted on the spring member having means adapted to be attached to the cover of the card case.

2. A card shifting attachment consisting of a spring member fitting in a card case having a slot longitudinally to the spring member, a card shifting mechanism slidably mounted in the slot of the spring member with one end, the other end being formed to be attached to the cover of the card case.

3. A card shifting attachment consisting of a frame fitting in a card case having a slot, an operating rod slidably and pivotally mounted in the slot of the frame with one end, lugs formed on the same end of the operating rod opposite to the pivot connection, card engaging means turnably mounted between the lugs, the second end of the operating rod being formed to be attached to the cover of the card case.

4. A card shifting attachment consisting of a frame substantially U-shape, one side of the U fitting evenly against the inside of the card case forming the support for card shifting mechanism while the other side of the U is bent forming a spring for pressing the cards against the card shifting mechanism in this attachment, and card shifting mechanism slidably mounted on the frame with one end adapted to be attached with the other end to the cover of the card case.

5. In a card case comprising a body part

and a cover part, a card shifting attachment consisting of a spring member fitting in the body part, and card shifting mechanism slidably mounted on the spring member with one end and being connected with the other end to the cover part of the case.

6. In a card case comprising a body part and a cover part, a spring member formed to be fitted into different sizes of card cases, 10 and card shifting mechanism slidably mounted on the spring member having means for engaging with the cover of the case only when such is opened.

7. In a card case comprising a body part 15 and a cover part, a card shifting mechanism slidably mounted in the body part having means engaging with the cover part when opening same and having other means projecting through the case for operation by hand.

8. In a card case comprising a body part and a cover part; a frame fitting in the body part consisting of an upright having a slot therein, another upright being formed as a 25 spring opposite and connected to the first named upright, and card shifting means slidably mounted in the slot of the first named upright between the two uprights attached to the cover part of the case.

30 9. In a card case comprising a body part and a cover part; a frame removably disposed in the body part of the case, a roller slidably mounted on the frame having means to engage with the cards in the case in one 35 direction disengaging in the opposite direction when so shifted.

10. In a card case, a card shifting roller 40 slidably mounted with the axis of the roller transversely to the shifting direction of the roller, card engaging means formed on the roller radially of the roller, and stopping means formed on the roller in engagement with the cards when shifted in one direction the said stopping means holding the 45 card engaging means on the roller out of engagement when shifting the roller in the opposite direction.

11. In a card case, card shifting means 50 slidably mounted, a roller turnably mounted on the shifting means transversely to the shifting direction, a pointed projection formed on the roller for card engaging

means, and two other projections formed on the roller, one of the last named projections resting against the shifting means 55 when the pointed projection engages with the cards in the case in the shifting direction while the other of the last named projections rests against the shifting means when operated in the opposite direction, and 60 the pointed projection being in position disengaged from the cards.

12. In a card case a frame fitting in the case, a card shifting rod slidably mounted on the frame with one end, the other end of 65 the shifting rod being formed for operating and connecting the shifting rod, a roller turnably mounted on the first named end of the card shifting rod transversely to the shifting direction of the shifting rod, card 70 engaging means formed on the roller projecting toward the cards in the case in the shifting direction, the card engaging means being disengaged from the cards when the shifting rod is operated in the opposite direction, and stopping means also formed on the roller in relation to the card engaging means.

13. In a card case comprising a body part and a cover part, a card shifting rod slidably 80 mounted in the body part of the case with one end, the other end of the shifting rod being formed to engage with the cover part of the case, a roller turnably mounted on the slidably mounted end of the card shifting 85 rod having means to engage with the cards in the case in the card shifting direction toward the cover part of the case, the roller having also stopping means in relation to the card engaging means on the roller, and 90 means provided in the card case opposite to the card shifting rod with the roller for holding the cards toward the roller, the cover of the case being provided with a slot adjacent to the card shifting rod in a position close to the edge of the card engaged by the card shifting rod.

In testimony whereof I hereunto affix my signature in the presence of two witnesses.
